UNITED STATES PATENT OFFICE.

WILLIAM B. RUNYAN, OF DAYTON, OHIO, ASSIGNOR TO MITCHELL RAIL ANCHOR COMPANY, INC., OF DAYTON, OHIO, A CORPORATION OF KENTUCKY.

RAIL ANCHOR.

Application filed June 5, 1922. Serial No. 565,873.

To all whom it may concern:

Be it known that I, WILLIAM B. RUNYAN, a citizen of the United States, residing at Dayton, in the county of Montgomery and State of Ohio, have invented certain new and useful Improvements in Rail Anchors, of which the following is a specification.

My invention relates to devices for preventing the longitudinal creeping movement of railway rails, devices of this class being commonly called anti-creepers, rail-stays, or rail anchors.

The invention has for certain of its objects the provision of an improved rail anchor which will be relatively light in weight, yet possess the necessary strength and rigidity to withstand the severe stresses to which devices of this character are subjected when in service, which may be easily applied to a rail, which may be applied to rails having base flanges of varying widths and be locked in its rail clamping position on such rails, and which is so formed that it may be made of cast metal without the use of cores in the mold in which it is formed, thereby effecting a substantial saving in the cost of labor and material in the manufacture of devices of this character.

Another object is to provide an improved rail anchor of a two piece type consisting of a yoke and a wedge, in which the wedge is so engaged with the yoke that it is held in alignment with an associated jaw portion of the yoke when it is being driven into wedging engagement between the rail and yoke member, and which is so formed that when in its wedging position it will permit the anchor to be driven to a slightly diagonal position across the rail base so as to effect a shackle hold on opposite edges of the rail base when such shackle hold is desirable.

Another and more specific object is to provide one of the members of the anchor with a bendable portion adapted to be bent into engagement with the other member of the anchor to lock the wedge member in position when the same is driven home and, when desired, to lock the wedge-key in an intermediate position, thereby accommodating rails having base flanges of different sizes without danger of the key—being not

fully driven home—backing out of its wedging engagement.

Another object is to provide a cast metal rail anchor having a yoke member formed with jaws which project over the upper surface of the rail base at opposite sides of the rail and a body portion which extends under the rail base, the portions of said body, adjacent said jaws being so formed as to provide openings beneath said jaws, whereby the "cores" heretofore used in the molds in which castings of this character are formed, are not required to form the yoke with the recessed jaw portions.

The invention has for further objects the novel constructions, arrangements and combination of parts and devices hereinafter described and claimed for carrying out the above stated objects and such other objects as will appear from the following description of a preferred embodiment of my invention.

I have shown a preferred embodiment of my invention in the accompanying drawing, wherein like characters of reference designate corresponding parts and wherein:

Fig. 1 is a plan view of a rail anchor constructed in accordance with my invention applied to the base flange of a railroad rail.

Fig. 2 is a cross section through the rail taken on line 2—2 of Fig. 1, showing my improved rail anchor in side elevation, and also illustrating in dotted lines the manner in which the yoke member is applied to the rail base.

Fig. 3 is a view in perspective of the yoke member of my improved rail anchor, and

Fig. 4 is a view in perspective of the key member employed in connection with the yoke member shown in Fig. 3.

In the accompanying drawing I have shown, in Figs. 1 and 2, my preferred type of rail anchor applied in its operative position on the base of a railway rail, indicated by the reference character 10, and abutting against one of the cross ties 11 on which the rail is supported.

The anchor device consists of a rail embracing yoke member 12 and a wedge key 13 adapted to be driven into wedging engagement between a portion of the yoke and the base flange of a rail. The yoke member 12, described more specifically, con-

sists of a body portion 14 which extends across a rail base and is formed at one end with a jaw portion 15 formed with a relatively short hook or lip member 16 which projects over the upper surface of one of the base flanges of the rail. The recess defined by said jaw portion is preferably of the same configuration as the edge of the rail base with which it is engaged. The other end of the body portion of the anchor is formed with a jaw portion 18 having a lip 19 which projects over the upper surface of the rail base at the other side of the rail. This jaw portion defines a recess 20 which is somewhat wider and deeper than the recess 17 and the vertical wall 21 thereof is spaced away from the adjacent vertical edge of the rail base when the anchor is in its applied position on the rail. The key 13 is in the form of a wedge and is preferably angular in cross section and is driven between the upper and vertical walls of the recess 20 and the adjacent edge of the rail base. The key is formed with a depending web 22 which intervenes between the vertical edge of the rail base and the wall 21 of the jaw 18 though does not, ordinarily, effect a wedging engagement with said wall or with the vertical edge of the rail base; the grip of the anchor on the rail being effected, preferably, by means of a wedging engagement of the key 13 with the inclined upper surface of the rail base and the under surface of the lip 19 of the yoke. The clearance between the wall 21 and the outer vertical wall of the key 13 permits the yoke to be driven to a slightly diagonal position across the rail base without affecting the wedging engagement between the key 13 and the lip 19 of the yoke, thereby providing in addition to the wedging frictional grip, above described, a shackle grip between the rear edge 27 of the jaw 15 and one edge of the rail and the forward edge 28 of the key 13 and the opposite edge of the rail base (Fig. 1) when the width of the rail base is such as to permit the yoke to be moved to such angular position. In order to maintain the key 13 in alignment with the jaw portion 19 of the yoke—that is to say, to prevent it from creeping upwardly on the inclined surface of the rail base, when it is being driven to its wedging position, I preferably form its upper surface with a groove 23 which receives a rib 24 formed on the lower surface of the lip 19 of the yoke member. When the key is driven home it may be locked in this position by bending downwardly a locking tongue 25 formed on the lip 19 of the yoke so that the tongue will assume a position back of a shoulder 26 formed on the upper surface of the key. If the rail base be of such size that the key 13 assumes a tight wedging engagement before it is driven entirely home, the key may be locked in such intermediate position by

bending the rear portion only of the lip 25 downwardly to a position back of the shoulder 26 of the key.

One end of the yoke member, preferably, the jaw end 15, is provided with a tie-abutting foot 34 which bears against one of the vertical faces of the adjacent cross tie 11.

In order to minimize the cost of manufacturing my improved anchor device, I preferably form the body portion of the yoke member adjacent its ends somewhat wider than the lips 16 and 19 of the jaws and form the body at points below the lips 16 and 19 with openings 29 and 30, respectively. These openings are preferably flush with the vertical walls 17 and 21 of the jaws and are of slightly greater area than the lips of the jaws so that the sand in the mold, in which the yoke is cast, may be divided along a line flush with the upper surface of the body of the yoke. The sand in the lower section of the mold extends through openings in the pattern corresponding to the openings 29 and 30 of the finished article and takes the impression from the pattern for the vertical walls of the jaws and the lower surfaces of the lips 16 and 19, thereby making it unnecessary to provide the mold with "cores" as has been heretofore customary in casting rail anchor yokes having overhanging lips of the above general character. The portions of the body surrounding the openings 29 and 30 are reinforced by vertically disposed strengthening ribs 31 and 32.

The key and yoke members for convenience are preferably bound together for shipment. This is expedited by providing the key with an opening 33 through which a wire or other suitable means may be passed to firmly attach the wedge 13 to the yoke, and thereby avoid danger of the wedge of any particular yoke being misplaced or lost in transit.

In applying the anchor to a rail, the yoke member is positioned under the rail with the lip portion 19 thereof projecting over one of the edges of the rail base in substantially the same manner as indicated in dotted lines in Fig. 2. The yoke is then raised to the full line position and moved laterally, that is, toward the left of Fig. 2 until the lip 16 of the jaw 15 is in firm engagement with the upper surface of the other side of the rail base. The yoke may then be positioned with the tie abutting foot engaging one of the vertical faces of the tie 11 and the key 13 driven into wedging engagement between the rail base and the lip 19 of the jaw 18.

If desired, however, the yoke may be positioned slightly away from the tie 11 and driven upon the key 13. In either event, when the key 13 has assumed the desired wedging position between the rail base and jaw 18 the tongue 25 may be bent downwardly so as to stand back of the shoulder 130

26 of the key and thereby lock the anchor in its applied position.

While I have described my invention in connection with one specific embodiment, it

5 will be obvious that the features above disclosed may be employed in connection with the manufacture of devices having different structural features from that shown and described herein, it will therefore be understood that I do not wish to confine myself to the various structural features shown and described except in so far as such specific limitations may appear in the appended claims.

15 I claim:

1. A rail anchor comprising a rail base engaging member and a wedge adapted to have a wedging engagement between said member and the upper surface of the rail base, said member and wedge being formed with coengaging means for maintaining the wedge in alignment with said member when the wedge is being driven to its operative position.

25 2. A rail anchor comprising a rail base engaging member and a wedge adapted to have a wedging engagement between said member and the upper surface of the base of the rail, said member and wedge being interlocked with each other to maintain the wedge in alignment with said member when the wedge is being forced to its operative position.

35 3. A rail anchor comprising a rail base engaging member having a jaw which projects over the upper surface of the rail base and a wedge adapted to have a wedging engagement between said jaw and the upper surface of the rail base, said member and wedge being interlocked with each other to maintain the wedge in alignment with said member when the wedge is being forced to its operative position.

40 4. A rail anchor comprising a rail base engaging member having a jaw which projects over the upper surface of the rail base, and a wedge adapted to have a wedging engagement between said jaw and the upper surface of the rail base, said jaw being provided with a rib and the wedge with a groove to receive said rib, whereby the engaging member and wedge have an interlocking engagement to maintain the wedge in alignment with said member while the wedge is being forced to its operative position.

45 5. A rail anchor comprising a rail engaging yoke formed at one end with a jaw to engage one edge of the base of the rail, at the other end with a jaw portion having a lip which extends over the other edge of the rail base, and a key member adapted to have a wedging engagement between said lip of the yoke and the adjacent edge of the rail base, said lip and key being formed to pro-

vide an interlocking engagement to maintain the key in substantial alignment with said lip when the wedge is being driven to its operative position.

6. A rail anchor comprising a rail base engaging yoke formed at one end with a jaw to engage one edge of the rail base, at the other end with a jaw portion having a lip which extends over the upper edge of the rail base, and a key member adapted to have a wedging engagement between said lip of the yoke and the adjacent edge of the rail base, said lip being formed with a rib and said key having a recess to receive said rib, whereby the key is interlocked with said lip so as to prevent the key from creeping upwardly on the rail base while it is being driven to its operative position.

7. A rail anchor comprising a rail base engaging yoke formed at one end with a jaw to engage one edge of the rail base, at the other end with a jaw portion having a lip which extends over the upper edge of said base, and a key member adapted to have a wedging engagement between said lip of the yoke and the adjacent edge of the rail base, said lip being formed on its under surface with a rib and said key having a recess on its top surface to receive said rib whereby the key is interlocked with said lip so as to prevent the key from creeping upwardly on the rail base while it is being driven to its operative position.

8. A rail anchor comprising a rail engaging yoke formed at one end with means for engaging one edge of a rail base and at the other end with a jaw having a lip which projects over the other edge of the rail base, a wedge adapted to be driven between said rail base and the lip of said jaw, means for maintaining the wedge in substantial alignment with said jaw while the wedge is being driven to its applied position, and means bendable on a line longitudinally of said wedge to lock said wedge in its applied position.

9. A rail anchor comprising a rail engaging yoke formed at one end with means for engaging one edge of a rail base and at the other end with a jaw having a lip which projects over the other edge of the rail base, a wedge adapted to be driven between said rail base and the lip of said jaw, means for maintaining the wedge in substantial alignment with said jaw while the wedge is being driven to its applied position comprising a rib formed on the under surface of said lip adapted to extend into a recess formed in the top surface of the key, and means bendable on a line longitudinally of said wedge to lock said wedge in applied position.

10. A rail anchor comprising a rail engaging member formed at one end with means for engaging one edge of a rail base and at the other end with a jaw having a lip which

- projects over the other edge of the rail base, a wedge adapted to be driven between said rail base and the lip of said jaw, means for maintaining the wedge in substantial alignment with said jaw while the wedge is being driven to its applied position comprising a rib formed on the under surface of said lip adapted to extend into a recess formed in the top surface of said wedge member, and a lug 10 on said lip which is bendable on a line longitudinally of said wedge to lock the same in its applied position.
11. A rail anchor comprising a yoke having jaws which extend over opposite edges 15 of the rail base, and a wedge key adapted to be driven between the rail base and one of said jaws, said wedge being formed with a shoulder and the yoke being formed with a lug bendable on a line longitudinally of said wedge to a position back of said shoulder.
12. A rail anchor comprising a yoke having jaws which extend over opposite edges 20 of the rail base, and a wedge adapted to be driven between the rail base and one of said jaws, said wedge being formed on one of its longitudinal surfaces with a shoulder and the yoke being formed with a lug bendable on a line longitudinally of said wedge to a position back of said shoulder.
13. A rail anchor comprising a yoke having jaws which extend over opposite edges 25 of the rail base, and a wedge adapted to be driven between the rail base and one of said jaws, and means for locking the wedge in various positions comprising a shoulder on 30 said wedge and a lug on the yoke adapted to be bent on a line longitudinally of said wedge so that a portion of said lug extends back of said shoulder.
14. A rail anchor comprising a yoke having jaws which extend over opposite edges 35 of the rail base and a wedge key angular in cross section which extends over the vertical edge and top surface of the rail base and is adapted to be driven between the rail base and one of said jaws, said wedge being formed with a shoulder and the yoke being formed with a lug bendable on a line longitudinally of said wedge key to a position 40 back of said shoulder.
15. A rail anchor comprising a yoke formed at one end with means for engaging one edge of a rail base and at the other end with a jaw having a wall spaced away from the vertical edge of the rail base at the other 45 side of the rail and with a lip portion which extends over the upper surface of the rail base, an angular key member having a portion intervening between said vertical edge of the rail base and said wall of said jaw which is normally out of engagement with said wall and with a portion adapted to have a wedging engagement with said lip and the upper surface of said rail base; said key member and jaw being so proportioned as to 50 permit the yoke member to assume a slight diagonal position across the rail base to effect a shackle hold of the anchor on opposite edges of said base.
16. A rail anchor comprising a cast metal member having a body portion and an angularly disposed jaw which together define a recess; the said body portion being formed with an opening below said angularly disposed jaw, for the purpose described. 55
17. A rail anchor comprising a cast metal member having a body portion and an angularly disposed jaw which overhangs a portion of said body and which together with said body define a recess adapted to receive one edge of a rail base; the said body portion being formed at a point below said overhanging portion with an opening, for the purpose described. 60
18. A rail anchor comprising a cast metal member having a body portion and an angularly disposed jaw which overhangs a portion of said body and which together with said body defines a recess adapted to receive one edge of a rail base; the said body portion being formed below said overhanging portion with an opening of greater area than said overhanging portion, for the purpose described. 65
19. A rail anchor comprising a cast metal member having a body portion and an angularly disposed jaw which overhangs a portion of said body to provide a recess adapted to receive one edge of a rail base; the said body portion being formed below said overhanging portion with an opening of greater area than said overhanging portion, for the purpose described, and formed with rigidifying ribs surrounding said openings. 70
20. A rail anchor comprising a rail base 105 embracing member having a body portion which extends under the base of a rail and formed at its ends with jaws having angularly disposed lips which project over the upper surfaces of the rail base, the said lips being made narrower than the ends of said body portion, and said body portion being formed with openings below said lip, for the purpose described. 110
21. A rail anchor comprising a rail base 115 embracing yoke having a body portion which extends under the base of a rail and formed at its ends with jaws having substantially vertical walls with angularly disposed lips, the latter of which project over the upper 120 surfaces of the rail base, the said lips being made narrower than the ends of said body portion and said body portion being formed with openings below said lips, one edge of the openings, in each case, being defined by 125 the inner face of said vertical wall portion of the adjacent jaw, for the purpose described. 130
22. A rail anchor comprising a cast metal member formed at opposite ends with an-

gularly disposed jaw portions adapted to overhang the upper surfaces of a rail base and a wedge key member, angular in cross section, adapted to be forced between one of said jaws and the adjacent edge of said rail base to effect a clamping engagement of said device on the rail; said jaw portions

being narrower than the ends of said body of the anchor and the said body being formed with openings below the said angularly disposed portions of said jaws for the purpose described.

WILLIAM B. RUNYAN.
